UNITED STATES PATENT OFFICE.

SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

LOCK.

Application filed October 2, 1922. Serial No. 591,685.

To all whom it may concern:

Be it known that I, SAMUEL SEGAL, a citizen of the United States, and a resident of New York, in the county of New York and 5 State of New York, have invented certain new and useful Improvements in Locks, of which the following is a specification.

My invention relates to locks and has for its principal object the production of a lock 10 of simple construction, certain parts of which shall be provided with means to facilitate the finding or locating of the key hole in the dark or under other abnormal conditions.

15 To the above ends my invention consists in the novel parts and combinations thereof hereinafter more particularly described and then specified in the claims.

Referring to the accompanying drawings 20 showing a practical embodiment of the invention:

Fig. 1 is a front elevation of a conventional form of cylinder lock showing the invention.

25 Fig. 2 is a horizontal section on the line 2—2 of Fig. 1.

Fig. 3 is a view similar to Fig. 1 but showing a modification.

30 Fig. 4 is a horizontal section on the line 4—4 of Fig. 3.

Referring in detail to the drawing, 1 indicates a portion of a door or other closure which is provided with an annular opening 2 extending therethrough. 3 indicates the 35 cylinder of an ordinary pin tumbler lock while 4 indicates the tumbler housing forming a part thereof and which supports pin tumblers therein (not shown). Said cylinder 3 is provided with an annular face or outer plate 5 preferably integral therewith and of a size permitting it to be received by the opening 2. The cylinder also has perforated screw-threaded ears 6 integral therewith receiving the screws 7 passing through 40 the rear or supporting plate 8, whereby the cylinder and adjacent parts may be held in proper position within and against forward withdrawal through the opening 2. I have also provided a conventional form of escutcheon ring 9 within which the face plate 5 is seated, the wall of said escutcheon extending outwardly beyond the surface of the face plate 5 and the edge thereof engaging the face of the door 1 as clearly indicated 45 in Fig. 2.

The cylinder 3 carries and supports the ordinary rotatable key plug 10 which is provided with a key hole or opening 11 therein. Said key plug is connected by a spindle or other connection, which preferably passes through an opening in the supporting plate 8, with the lock mechanism which is housed in a suitable casing mounted on the inside of the door. The spindle or other connection, the lock mechanism and the casing 60 therefor, however, are not shown in the drawing as they may be of any convenient form and construction and form no part of the present invention. The lock is operated in the usual manner by insertion of a key in the key hole 11 and by a turning of the key which rotates the key plug 10 and operates the lock mechanism.

The face plate 5 is provided with a slot or groove 12 the walls of which are beveled or inclined inwardly as illustrated in Fig. 2. This slot is in alignment with the key hole 11 and extends through the key plug 10. It also preferably extends from one side of the face plate to the other side and meets or 70 communicates with the side wall of the escutcheon ring 9.

If it is desired to locate the key hole or opening 11 in the dark by means of the proper key so as to actuate the lock mechanism, the end of the key is brought into contact with the outer surface of the face plate 5 and then with the wall of the escutcheon ring 9. It is then moved around said wall within the slot or groove 12, after which it is pressed downwardly or upwardly, as the case may be, in said slot until it registers or is brought within the key hole or opening 11. The particular construction described and shown prevents the troublesome and time-consuming "feeling" for the key hole as the escutcheon ring 9, as well as the slot or groove 12, in conjunction, and separately, provide a guiding means whereby the end of the key is brought into proper position within the key hole without difficulty.

In the modification shown in Figs. 3 and 4 I dispense with the straight slot or groove 12 shown in the preferred form of the invention. In this case I provide a portion of the face plate 5 with a depressed portion which I have indicated at 13, this depressed portion forming with the raised or normal portion of the face plate, a ridge 14 which com- 100 105 110

municates with or extends to the walls of the escutcheon ring 9 as well as the key hole 11. To find the key hole or opening the end of the key is brought into contact with either 5 the raised or depressed portion of the face plate and, if necessary, moved until brought into contact with the side wall of the escutcheon ring, after which it is moved along said side wall until it contacts with or engages the ridge 14, whereupon it is moved 10 along said ridge until it reaches the key hole or opening 11.

It will be appreciated that my invention is not limited to any specific construction of 15 lock but may be applied with equal advantage to locks other than those of the pin tumbler type. It will also be understood that the invention is not limited to an annular face plate nor is it limited to a ring-shaped escutcheon as the face plate and escutcheon may have other configurations if 20 so desired.

What I claim as my invention is:—

1. In a lock, an annular face plate provided with a key hole therein, an escutcheon 25

ring surrounding said face plate and guiding means communicating with said key hole and said escutcheon ring and meeting said ring at opposite sides thereof.

2. In a lock, a face plate provided with 30 a guiding slot therein and a key plug mounted in said face plate and provided with a key hole therein, said key plug also having a guiding slot registering with said first-mentioned guiding slot.

3. In a lock, an annular face plate provided with a guiding slot therein, an escutcheon ring surrounding said face plate and a key plug mounted in said face plate and having a key hole therein, said key plug 40 also being provided with a guiding slot registering with said first-named guiding slot.

Signed at New York in the county of New York and State of New York this 30th day of September A. D. 1922.

SAMUEL SEGAL.
